(57) CLAIM

We claim the ornamental design for a night light, as shown and described.

DESCRIPTION

FIG. 1 is a perspective view of a night light embodying the invention;

FIG. 2 is a front view of the night light of FIG. 1;

FIG. 3 is a top view of the night light of FIG. 1;

FIG. 4 is a left side view of the night light of FIG. 1, the right side view being a substantial mirror image thereof;

FIG. 5 is a rear view of the night light of FIG. 1; and,

FIG. 6 is a bottom view of the night light of FIG. 1.

The broken lines showing of the environment are for illustrative purposes only and form no part of the claimed design.
